DESIGN FOR A PLAQUE OR SIMILAR ARTICLE

Harvey J. Williams, White Plains, N. Y.

Application March 27, 1940, Serial No. 91,278

Term of patent 14 years

To all whom it may concern:

Be it known that I, Harvey J. Williams, a citizen of the United States, residing at White Plains, in the county of Westchester and State of New York, have invented a new, original, and ornamental Design for a Plaque or Similar Article, of which the following is a specification, reference being had to the accompanying drawing, forming part thereof.

While the novel design is shown in the form of a plaque, it is contemplated that the same can be incorporated into other similar articles.

I claim:

The ornamental design for a plaque or similar article, as shown and described.

HARVEY J. WILLIAMS.
